UNITED STATES PATENT OFFICE

2,452,940

RAILWAY CAR SIDE BEARING

Neal F. Lane, Arkansas City, Kans.

Application December 14, 1945, Serial No. 634,907

6 Claims. (Cl. 308—226)

1

My invention relates to improvements in side bearings for railroad cars.

An important object of the invention is to provide a side bearing assembly which is easily adjusted to various elevations without necessitating removal of the railroad car to a shop.

A further object of the invention is to provide a side bearing which when assembled for use will not allow the bearing shaft and roller to become disengaged from the casing or box.

A further object of the invention is to provide means whereby the shaft which carries the roller will prevent the separation of the adjustable wedges from their adjusting pins.

A further object of the invention is to provide a side bearing which may be adjusted to various elevations, and which may be locked in those adjusted positions.

Further objects are to provide a side bearing of the above mentioned type, which is simple in construction, easy to assemble and disassemble, and which is strong and durable.

Other objects and advantages of the invention will be apparent during the course of the following description.

In the accompanying drawings forming a part of this application, and in which like numerals are employed to designate like parts throughout the same,

Figure 1 is an end elevation of a railroad car truck, showing my side bearings applied thereto,

Figure 2 is a vertical longitudinal section taken on line 2—2 of Figure 3,

Figure 2^a is a side elevation, partly diagrammatic, showing the adjustable wedge generally vertical and the generally spherical head threaded through the open end of the generally cylindrical recess,

Figure 2^b is a similar view, showing the adjustable wedge in a tilted position, beneath the shaft shifted to the uppermost position, showing the spherical head retained within the cylindrical recess,

Figure 3 is a plan view of a side bearing embodying my invention,

Figure 4 is a vertical transverse section taken on line 4—4 of Figure 3,

Figure 5 is a side elevation of one of the adjustable wedges, showing one end in section, and,

Figure 6 is an end elevation of the wedge.

In the drawings, wherein for the purpose of illustration is shown a preferred embodiment of my invention, the numeral 1 designates a railroad car bolster, arranged above the usual truck bolster 8; and pivoted thereto by means embodying

2

the usual king pin 9. Arranged on opposite sides of the pivot 9 are my side bearings 10.

Each side bearing 10 embodies a preferably rectangular casing or box 11, having its longitudinal axis extending transversely of the truck bolster 8. This casing or box 11 is provided at opposite sides and adjacent to its bottom, with mounting flanges or ears 12, preferably formed integral therewith, which flanges or ears are provided with openings 13 for bolting the same to the bolster 8. Arranged within the casing or box 11, and extending longitudinally thereof in parallel relation to the sides of the same, are partitions or walls 14, preferably integral with the casing or box 11. These partitions are vertically arranged, and are provided with vertically elongated openings or slots 15 closed at their tops and bottoms. Within the casing 11 and between the partitions 14 and casing side walls 16, one of which is provided with an opening 17, are stationary wedges 18, preferably formed integral with the casing, and having their upper surfaces 19 inclined and substantially smooth. Formed upon, integral with and extending longitudinally thereof for the full length of the upper surfaces 19, are shoulders or guides 20.

Arranged upon the stationary wedges 18 are adjustable wedges 21, the top surfaces 22 of which are horizontal in assembly, and the bottom surfaces 23 of which are inclined, corresponding to the inclination of the tops of the stationary wedges 18. The bottom surfaces 23 of the adjustable wedges 21 are substantially smooth, and have formed thereon, and extending longitudinally thereof for the full length of said lower surfaces, recesses 24, which slidably receive the corresponding shoulders or guides 20 on the stationary wedges 18. The adjustable wedges 21 are provided with substantially cylindrical vertical recesses 25, extending from the top surfaces 22 downwardly, and terminating short of the bottoms of the adjustable wedges. The wedges 21 are provided in their outer ends with vertical slots 25' which lead into the recesses 25.

The numeral 26 designates a shaft which is horizontally arranged within the vertically elongated slots 15, and rests upon the horizontal top surfaces 22 of the adjustable wedges 21. The numeral 27 designates a roller, provided with an opening 28, to removably receive the shaft 26.

The numeral 29 designates pins for longitudinally adjusting the wedges 21 to a higher or lower elevation. Each pin 29 has a screw-threaded portion 30, to engage within a screw-threaded opening 31, in the end wall 32 of the casing or box 11.

The adjusting pin 29 is provided at its inner end with a reduced cylindrical neck 33, having a substantially spherical head 34. The spherical head 34 engages within the substantially cylindrical recess 25, and the neck 33 extends through the slot 25'.

Each adjustable pin 29 is further provided at its outer end with a preferably rectangular extension 35, adapted for engagement with a wrench or the like. Each extension 35 has a transverse opening 36 to receive the end of a locking wire 37.

In operation, the car bolster 7 has its outer or lower surfaces adapted to engage or rest upon the rollers 27, when the car rocks or sways. When it is desired to vertically adjust the rollers 27 upwardly, the adjustable wedges 21 are shifted longitudinally toward the upper ends of the stationary wedges 18, by turning the adjusting pins 29 in the proper direction. These rollers may be lowered by turning the pins 29 in an opposite direction. These adjustments may be made without bringing the car to a shop or even removing it from the train. After the adjustments have been made, the wedges 21 may be locked in position by inserting the ends of the wire 37 into the openings 36. This locks the pins 29 against turning movement.

In assembling the side bearing, the pin 29 may be screwed in for a short distance, slightly beyond the position shown in Figure 2. The wedge 21 is introduced into the space between the partition 14 and side 16, and is generally vertically arranged with its recess 25 lowermost and generally horizontal. When the wedge 21 is in this position, the head 34 may be threaded into the open end of the recess 25 while the neck 33 enters the slot 25'. The wedge 21 is now dropped to the horizontal position in engagement with the wedge 18. The wedges 21 are now in the lowered position at the elevation of the lower portion of the opening 17 or slightly beneath it. The roller 27 is now placed between the partitions 14 and the shaft 26 is passed through the opening 17, opening 28 in the roller and through the vertical slots 15. The shaft 26 now extends beyond the opposite ends of the roller 27 above the wedges 21 and the ends of the shaft 26 are disposed inwardly of the sides 16. The wedges 21 will support the shaft 26 and roller when the roller is released. The wedges 21 are now adjusted upwardly so that the shaft 26 becomes eccentric with the opening 17, and therefore cannot pass through the opening 17. The roller 27 is now adjusted to the uppermost position for engagement with the bolster 7, when it rocks or sways. As the bearing or king pin 9 wears, the roller 27 and shaft 26 are lowered, by manipulation of the wedges 21, but they are never lowered sufficiently so that the shaft will become concentric with the opening 17 and can pass through this opening. The shaft 26 is therefore positively held within the casing 11 against endwise displacement by the sides 16, and against vertical displacement by the upper closed ends of the slots 15. The shaft 26 also prevents the wedges 21 from approaching the vertical position so that these wedges could become disconnected from the spherical heads 34, since these wedges are arranged beneath the shaft 26 and the upward movement of the shaft is limited by engaging the closed ends of the slots 15. Figure 2a shows the wedge 21 in the generally vertical position to thread the head 34 into the recess 25, while Figure 2b shows the shaft 26 in its uppermost position, and the wedge 21 inclined but not sufficiently to

permit of the separation of this wedge and head 34. The wedge is therefore permanently secured to its adjusting pin 29 when the shaft 26 is in place within the casing.

5 It is to be understood that the form of my invention herein shown and described is to be taken as a preferred example of the same, and that various changes in the shape, size and arrangement of parts may be resorted to without departing from the spirit of my invention or the scope 10 of the subjoined claims.

Having thus described my invention, what I claim is:

1. A side bearing assembly for a railway car, 15 comprising a casing including sides and partitions spaced from the sides and from each other, said partitions having elongated generally vertical slots closed at their tops, one side having an opening, spaced lower wedges arranged within the casing, upper adjustable wedges arranged 20 within the casing and supported by the lower wedges, substantially horizontal pins having screw threaded engagement with the casing, self adjusting means connecting the adjustable wedges and pins so that the pins may shift such wedges longitudinally and the wedges may move vertically with respect to the pins, a roller arranged 25 between the partitions and having an opening, a shaft removably mounted within the opening and adapted to be arranged inwardly of the sides, the shaft being passed endwise through the opening in the side and held against endwise displacement when it is eccentric with respect to such opening.

2. A side bearing assembly for a railway car, 30 comprising a casing including sides and partitions spaced from the sides and from each other, said partitions having upstanding elongated slots closed at their upper ends, one side having an opening, spaced lower wedges arranged within the casing between the sides and partitions, upper 35 adjustable wedges supported by the lower wedges, the adjustable wedges having generally cylindrical recesses and elongated slots leading into the recesses, adjusting screws engaging the casing and having generally spherical heads to enter the generally cylindrical recesses and shanks to pass through the slots of the recesses, a roller arranged 40 between the partitions and having an opening, and a shaft removably mounted within the opening of the roller and adapted to be arranged inwardly of the sides and disposed above the upper 45 adjustable wedges, the shaft being passed endwise through the opening in the side and held against endwise displacement when it is eccentric with respect to such opening, the vertical movement of the shaft being limited when it engages the closed ends of the upstanding slots in the partition, the shaft then serving to limit the upward swinging of the adjustable wedges so that they cannot become separated from the generally 50 spherical heads.

3. A side bearing assembly for a railway car, 55 comprising a casing having inclined faces, adjustable wedges mounted upon the inclined faces, each wedge being provided near one end with a transverse generally cylindrical recess and a slot leading into the side of the recess, the upper end of the recess being open and its lower end closed, an adjusting screw engaging the casing for coaction with each adjustable wedge and having a shank and generally spherical head, the head being adapted to be inserted into the open end of the generally cylindrical recess and the shank 60 passed into the slot of the recess, a shaft ar- 65

ranged above the adjustable wedges, and a roller carried by the shaft.

4. In a side bearing assembly for a railway car, an adjustable wedge provided near one end with a transverse generally cylindrical recess having one end open and its opposite end closed and having a transverse slot leading into the recess, and an adjusting screw having a shank and generally spherical head, the head being adapted to be inserted into the open end of the recess and the shank passed into the slot.

5. A side bearing assembly for a railway car, comprising a casing having inclined faces, adjustable wedges mounted upon the inclined faces, adjusting screws engaging the casing and having swiveled connections with the wedges, said screws having extensions to be engaged by a tool, said extensions having transverse openings, a locking wire having its ends inserted into the transverse openings, a roller within the casing, and a shaft carrying the roller and arranged above the wedges.

6. A side bearing assembly for a railroad car, comprising a casing having inclined faces, ad-

justable wedges mounted upon the inclined faces, each wedge being provided near one end with a transverse recess and a slot leading into the side of the recess, the upper end of the recess being opened and its lower end closed, an adjusting screw engaging the casing for coaction with each adjustable wedge and having a shank and head, the head being adapted to be inserted into the open end of the transverse recess and the shank passed into the slot of the recess, a shaft disposed above the adjustable wedges, and a roller carried by the shaft.
